QUICK-ACTION TYPE VISE HAVING PAWL-LOCKED SLIDABLE JAW

Janne Walfrid Jansson, Malung, Sweden

Application March 24, 1949, Serial No. 83,257
In Sweden April 12, 1945

4 Claims. (Cl. 81—30)

1

My invention relates to certain improvements in vises of the so-called quick action type wherein the movable member of the vise may be quickly adjusted so as to be brought to a desired position within a relatively short time.

An object of the invention is to provide a vise of the quick action type having a pawl locked jaw, provided with spaced runners which render the jaw displaceable longitudinally along a slide which also includes spaced runners that are guided in a passage in the body of the vise that carries the fixed jaw. The runners of the jaw and the runners of the slide are spaced from each other in order to provide a vertical passageway between them thus enabling the vise to be used for gripping a long workpiece inserted between the jaws.

A further object of the invention is to provide a pawl-and-ratchet device giving a relatively fine adjustment of the movable jaw.

Another object is to provide a device for a coarse adjustment of the movable jaw to any desired position.

These objects I attain as hereinafter set forth, reference being had to the accompanying drawings, in which:

Fig. 1 is a top view of my vise.

Fig. 2 is a longitudinal sectional elevation of one embodiment of the vise, the jaws being nearly closed.

Fig. 3 is a longitudinal sectional elevation similar to Fig. 2, showing the jaws in an opened position.

Fig. 4 shows half of the section on the line IV-IV of Fig. 3.

Fig. 5 is a perspective view of the pawl.

Fig. 6 is a longitudinal sectional elevation of a second embodiment having two rows of rack-teeth.

Fig. 7 is a section on the line VII-VII of Fig. 6.

Fig. 8 is a perspective view of the pawls used in the embodiment shown in Fig. 6.

Fig. 9 is a top view of a part of the bottom of the body member carrying the fixed jaw.

Fig. 10 is a longitudinal sectional elevation of a third embodiment of the vise.

Fig. 11 is a section on the line XI—XI of Fig. 10.

Fig. 12 is a perspective view of the pawl used in the third embodiment.

Fig. 13 is an exploded plan view with parts in section of the embodiment of Figs. 1-5, and

Fig. 14 is a right hand end view of Fig. 1.

Referring first to the construction of Figs. 1 through 5, the vise comprises a hollow body member 1 which is provided with lugs 2 having holes 3 for bolts for securing the body member to a bench or the like in the usual manner. Preferably made in one piece with the body member 1, is a jaw 4 which cooperates with a second, movable jaw 5 for holding the work in the usual manner. The jaw 5 is slidably connected by means of a screw 6 with a slide 7 which may be displaced in the body member 1. The screw 6 is in the usual manner provided with a bolt head 8 which extends on the outside of the slide 7 and which is provided with a lever 9.

As will be clear from Fig. 4 the lower portion of the body member is hollow so as to leave a passage for the slide 7 which is provided with runners 10 sliding on shelves 11 at the sides of the passage in the body member. In holes 12 in said runners 10 there is arranged a stud 13 carrying a robust pawl 14 which cooperates with a series of rack-teeth 15 in the centre of the bottom of the passage in the body member 1. The surfaces 16 and 17 of the pawl 14 and the teeth 15, respectively, engaging each other are undercut in such a way that the pawl 14 from a position on the top of a tooth will immediately fall down on to the bottom of the space between said tooth and the next when the pawl releases the edge of the top. In this way the pawl and the teeth cannot mesh with one another in intermediary positions which will of course not afford the same security as the position of meshing in which the pawl completely meshes with a tooth, as is shown in Fig. 2.

The jaw 5 is also provided with runners 16' which may slide on shelves 17' provided on the inside of the runners 10 of the slide 7. Instead the runners 16' may also slide on the shelves 11 for the runners 10. The upper portion of the runners 16' ends in an inclined edge 18 so as to provide clearance for the lateral portions of the pawl 14 and the stud 13 while the lower portions 19 of the runners 16' extend behind the pawl. At their free end the extensions 19 are provided with a projection 20 turned upwards, which projections engage corresponding shoulders 21 on the pawl 14 when the jaw 5 is displaced from the jaw 4 by turning the lever 9 as is shown in Fig. 3. By this engagement the pawl 14 is turned counter-clockwise out of meshing with the teeth 15.

At the free end the aperture between the runners 10 of the slide 7 is closed rearwards and upwards by means of a plate 22 bent at an

angle. Further a plate 23 covers the centre of the opening of the passage in the body member 1 below the jaw 4.

As will be clear from the above, there is a free passage between the runners 10 and 16 just below the gap between the jaws 4 and 5 so that a long work piece which is vertically clamped between the jaws may pass down in the opening between said runners 10 and 16.

In using the vise according to the invention it is necessary for displacing the jaw 5 away from the jaw 4 to turn the lever 9 so as to displace the jaw 5 in relation to the slide 7 until the projections 20 on the extensions 19 engage the shoulders 21 on the pawl 14 and bring the latter out of engagement with the rack-teeth 15. The jaw 5 may then together with the slide 7 be drawn to the right in Fig. 3 a desired distance whereupon a work piece placed between said jaws may be gripped by first moving the slide 7 and the jaw 5 to the left as a unit, the pawl 14 jumping from tooth to tooth if the pawl is not brought out of engagement with the rack-teeth 15, and then by moving the jaw 5 with respect to the locked slide 7 by operating the screw 6. The stroke of the jaw 5, which may be effected by means of the screw 6 should be a little larger than the distance between two adjacent teeth 15.

The embodiment illustrated in Figs. 6-9 differs from the embodiment just described in that there are provided two series of rack-teeth each co-operating with a separate pawl, which series are displaced in relation to each other. In this way the distance between two locking positions of the pawl-and-ratchet device will only be half of the corresponding distance in the embodiment illustrated in Figs. 1-5. Thus the necessary turning of the screw 6 is reduced.

In the construction of Figs. 6-9 two pawls 14' and 14'' are pivoted on the stud 13, said pawls being separated by means of a spacing washer 24. The pawls 14' and 14'' cooperate with two series of rack-teeth 15' and 15'' which are displaced relatively to each other in the direction of movement of the jaw 5 such a distance that the teeth 15' are situated just opposite the spaces between the teeth 15''. Thus, the necessary maximal displacement of the slide 7 relatively to the body member 1 in order to bring a pawl into engagement with a tooth is only half of the necessary displacement when only one series of rack-teeth is used having teeth of the same size.

In order to further reduce the maximum displacement which is necessary, of course, more than two series of rack-teeth may be used, but as the displacement has already been reduced to the half by means of two series, this is in the most cases sufficient in practice.

The pawls 14' and 14'' are actuated in the same manner as described with reference to Figs. 1-5, the pawls being provided with a shoulder 21' and 21'' respectively against which the projections 20 abut. Preferably, the projections are connected to each other by means of a bridge 29.

The operation of the embodiment illustrated in Figs. 6-9 is substantially the same as that of the embodiment illustrated in Figs. 1-5.

The third embodiment illustrated in Figs. 10-12 has a locking device operating by wedge action and permitting a coarse adjustment of the movable jaw to any desired position. In this embodiment the pawl 25 is provided with a recess 26 at the lower edge, said recess tapering towards its bottom. The shape of the recess 26 corre-

sponds to the shape of a rail 27 provided in the centre of the bottom of the passage in the body member 1. When the pawl 25 is free to turn down towards the rail 27 it will prevent the slide 7 from being displaced away from the fixed jaw 4 by means of the wedging of the recess 26 on the rail and the wedging action increases according to the power with which one tries to move the slide 7 away from the fixed jaw 4. In order to ensure that the pawl 25 does not fasten in the position where it is out of engagement with the rail, it may be actuated by a spring, for instance, a leaf spring (not shown) secured to the angle plate 22, which tends to bring the pawl into engagement with the rail.

To the covering plate 23 there is secured a leaf spring 28 which prevents the pawl 25, owing to a certain elasticity of the material of the plate 23, from coming into engagement with the rail so close to the plate 23 that this plate then prevents the pawl from being turned out of engagement with the rail 27. However, owing to the elasticity of the spring 28 the pawl may always be turned counter-clockwise in Fig. 10.

Due to the fact that the pawl may be brought into engagement with the rail in any position, the necessary movement of the jaw 5 by means of the screw 6 may be made very small, the vise thus being usable in a very comfortable way.

In comparison with the embodiments previously described the last-mentioned embodiment has also the advantage that the movement of the jaw 5 against the jaw 4 is carried out silently even when the pawl 25 is turned down against the rail 27 so that one is spared the rattling noise of the pawl jumping from one tooth to the next.

What I claim is:

1. A vise comprising a body having a fixed jaw, a passage in said body, a slide comprising spaced runners guided in said passage, a movable jaw displaceably connected to said slide, a device for locking said slide against movement relative to said body, said locking device comprising at least one pivoted pawl for engaging corresponding locking means arranged in said body, said movable jaw being provided with spaced runners formed so as to abut against a projection of said pawl in a certain position of said movable jaw relative to said slide for swinging said pawl out of engagement with said locking means in said body, the runners of said slide and the runners of said movable jaw being spaced in order to provide a passageway between them for a workpiece inserted between said jaws.

2. A vise comprising a body having a fixed jaw, a passage in said body, a slide comprising spaced runners guided in said passage, a movable jaw displaceably connected to said slide, at least one series of rack-teeth in the bottom of said passage, a pawl for each series of rack-teeth for engagement with said teeth, said pawl being pivoted to said slide, said movable jaw being provided with spaced runners having a projection for abutting against a portion of said pawl in a certain position of said movable jaw relative to said slide for swinging said pawl out of engagement with said teeth, the runners of said slide and the runners of said movable jaw being spaced in order to provide a passageway between them for a workpiece inserted between said jaws.

3. A vise comprising a body having a fixed jaw, a passage in said body, a slide comprising spaced runners guided in said passage, a movable jaw displaceably connected to said slide, two series of rack-teeth in the bottom of said passage, said

series of rack teeth having their teeth relatively displaced in the direction of movement of said slide, a pawl for each series of rack-teeth for engagement with the corresponding teeth, which pawl is pivoted to said slide, said movable jaw being provided with spaced runners having a projection for abutting against a portion of said pawls in a certain position of said movable jaw relative to said slide for swinging said pawls out of engagement with their corresponding teeth, the runners of said slide and the runners of said movable jaw being spaced in order to provide a passageway between them for a workpiece inserted between said jaws.

4. A vise comprising a body having a fixed jaw, a passage in said body, a slide comprising spaced runners guided in said passage, a movable jaw displaceably connected to said slide, a rail in the bottom of said passage tapering upwards, a pawl having a recess corresponding to the form of said rail for wedging engagement with said rail, said pawl being pivoted to said slide, said movable jaw being provided with spaced runners having a projection for abutting against a portion of said pawl in a certain position of said movable jaw relative to said slide for swinging

5 said pawl out of engagement with said rail, the runners of said slide and the runners of said movable jaw being spaced in order to provide a passageway between them for a workpiece inserted between said jaws.
